UNITED STATES PATENT OFFICE

103,861

DESIGN FOR A PACKING SHEET

Walter H. Randall and Wallace E. Parsons,
Waterville, Maine, and Walter J. Schwertfeger, West Englewood, N. J., assignors, by mesne assignments, to The Canal National Bank of Portland, Portland, Maine, a national banking association, as trustee

Application August 3, 1936, Serial No. 64,197

Term of patent 14 years

To all whom it may concern:

Be it known that we, Walter H. Randall, Wallace E. Parsons, and Walter J. Schwertfeger, citizens of the United States, the said Randall and Parsons both residing at Waterville, county of Kennebec, State of Maine; and the said Schwertfeger residing at West Englewood, county of Bergen, State of New Jersey, have invented a new, original, and ornamental Design for a Packing Sheet, of which the following is a specification, reference being had to the accompanying drawing, forming part thereof.

Fig. 1 is a top plan view of a packing sheet showing our new design,

Fig. 2 is an edge view of the same, and

Fig. 3 is a fragmentary bottom view thereof.

We claim:

The ornamental design for a packing sheet, as shown.

WALTER H. RANDALL.

WALLACE E. PARSONS.

WALTER J. SCHWERTFEGER.
